COMBINATION CLOTHES HANGER

Original Filed March 15, 1939

UNITED STATES PATENT OFFICE

2,420,885

COMBINATION CLOTHES HANGER

Axel R. Kjeldsen, Kearney, N. J., assignor of one-half to Knud G. Keldsen, New York, N. Y.

Substitute for abandoned application Serial No. 261,926, March 15, 1939. This application May 2, 1946, Serial No. 666,619

4 Claims. (Cl. 223—88)

1

This application is a substitute for an abandoned application, filed March 15, 1939, under Ser. No. 261,926.

This invention relates to new and useful improvements in combination clothes hangers, and it has for its object to provide a combination clothes hanger, which will serve to keep the clothes in perfect shape and excellent condition, when they are not in actual use. Thus by employing the said clothes hanger, the clothing, whether it be a pair of trousers, a skirt or a jacket will be under a certain tension, and be subject to a stretching imparted to said pieces of clothing along the crease lines, for instance, the trousers, thereby preserving said crease, while at the same time during said stretching process any fold, which may have formed in the clothing, will be automatically removed.

By the special construction of my device, the jacket will in like manner retain its shape and form of the shoulders, eliminating at the same time, the unsightly wrinkles which otherwise invariably form right under the shoulder parts.

Furthermore, a special construction is provided, whereby to impart to and retain a definite and conspicuously sharp crease in the trousers. This latter object has been accomplished by tapering the outer ends of the brackets holding the trousers to a comparatively sharp edge.

With the above and other objects in view, this invention consists of the novel features of construction, combination and arrangement of parts, hereinafter fully described, claimed and illustrated in the accompanying drawings, forming part of this application, and in which similar characters of reference indicate corresponding parts in all views, and in which:

Figure 1 is a front elevational view of my invention.

Figure 2 is a transverse sectional view taken on the line 2—2 in Figure 1.

Figure 3 is a top plan view of an automatically adjustable shoulder member of my device.

Figure 4 is a side elevational view of said shoulder member, showing a slight modification therein.

Figure 5 is a side elevational view showing another form of my invention.

Figure 6 is a transverse sectional view taken on the line 6—6 in Figure 5; while

Figure 7 is a transverse sectional view taken on the line 7—7 in Figure 5.

Referring more particularly to the drawings, 10 indicates the conventional form of a clothes hanger; 11 indicates a bar fixedly secured to the

2

latter in any suitable manner. Two block members 12, 12 are formed with central bores in the upper part thereof, as may be noted in dotted lines at 13, whereby said block members are made to slide upon the bar 11. A rod 14, terminating at one end in a handle 15, is slidably mounted in the hanger 10 and bar 11, through vertical holes 16 and 17 formed in said hanger and bar, respectively.

10 The bar 14 is at its lower end formed with an enlargement 18; two bars 19, 19 have one end thereof pivotally mounted in the latter, as shown at 20, while the other ends of said bars 19, 19 are pivotally hinged to the block members 12, 12, as indicated at 21. A pulling, or pushing movement with respect to the rod 14 will, as may clearly be noted, actuate the bars 19, 19 and thus tend to, respectively, separate or draw together the block members 12, 12, as the latter slide upon the bar 11.

25 The block members 12, 12 have mounted thereon a rubber cover 22 in order to obtain a friction surface so that the pieces of clothing hung upon said block members 12, 12 will not easily slide off said members; said clothing pieces are thus held by the block members, as these are separated by manipulating the rod 14 to the extent of engaging in a taut manner, for instance, a skirt 23, as shown in part, in Figure 1.

30 In Figure 5 the construction is substantially similar, as hereinbefore described with respect to Figure 1, with the exception that the block members 12, 12 are substituted by block members 12', 12', which latter have their lower portions formed into bifurcated sections 24, 24, as shown especially in Figure 6, slanting toward one end 25, as shown especially in Figure 7, whereby to engage the trousers 26 at the crease lines 27; said block members 12', 12' may also have mounted thereon a rubber covering 22' for the purposes, as hereinbefore described.

35 In Figure 1 is further shown a shoulder member 28 hingedly attached to the hanger proper, as indicated at 29.

40 These shoulder members, of which there is one on each side, are adapted to accommodate the shoulder section of a jacket, etc.; they are actuated by the bars 30, 30, which, in turn, are pivotally connected to the bars 19, 19 and to said shoulder members, as indicated at 31 and 32, respectively.

45 It will be obvious that the rod 14 will, when manipulated, actuate not only the bars 19, 19, but also through the latter bars 30, 30, which in turn, will bring the shoulder pieces 28, 28 into

proper contact with the shoulders of a jacket, etc.

The bars 30, 30, are arranged upon opposite sides of the cross bar 11, while small, reduced portions 37 on the crossbar serve to permit a free play of the bars 30, 30 during the manipulation of these.

When it is desired by an individual to fit in an exact manner a certain size of a jacket, or dress, or in case of more expensively manufactured specimens of my device, the shoulder piece 28 may be provided with a longitudinally slidable attachment 34, as shown in Figure 4, which attachment may be adjusted to the exact width of the shoulders of the jacket or dress to be accommodated; said attachment may be secured to the shoulder piece 28 by means of a small screw 35, which latter is adapted to move in a slotted portion 36 indicated in dotted lines in Figure 3.

It will be understood that any part of the invention may be made of any suitable material.

It is obvious that changes may be made in the form, arrangement of parts, and construction shown and described herein without departing from the spirit of my invention, and I do not, therefore, wish to limit myself to the exact construction set forth herein, but reverse to myself to make such changes which are well within the claims attached hereto.

What I claim as new, and desire to secure by Letters Patent of the United States, is:

1. In a device of the class described, a coat hanger, a cross bar fixedly secured to the latter, block members slidably mounted upon said cross bar, a vertical rod movably extending through the coat hanger and the cross bar, an enlargement formed at the bottom of said vertical rod, crosswise arranged members pivotally mounted in said enlargement, said crosswise arranged members having their other ends pivotally attached to the block members, the latter terminating at their lower ends in bifurcated sections, said bifurcated sections having their outer end portions tapered to a substantially sharp edge, whereby to engage the crease in a pair of trousers, and a handle upon the end of the vertical rod, whereby to manipulate the device and cause the block members to move towards or away from each other.

2. A clothes hanger comprising an upper member having the form of a conventional hanger and adapted to accommodate a coat, a cross bar

fixedly secured to said hanger, block members slidably mounted upon the cross bar, a vertical rod slidably extending through the said hanger and cross bar, crosswise arranged members pivotally attached to the vertical rod and block members, top members hingedly secured to the hanger, and bars pivotally attached to said top members and to the crosswise members, the latter and the bars being actuated by the said vertical member.

3. A clothes hanger comprising an upper member having the form of a conventional hanger and adapted to accommodate a coat, a cross bar fixedly secured to said hanger, block members slidably mounted upon the cross bar, a vertical rod slidably extending through the said hanger and cross bar, crosswise arranged members pivotally attached to the vertical rod and block members, top members hingedly secured to the hanger, and bars pivotally attached to said top members and to the crosswise members, said top members being formed with slots therein, extensions adapted for attachment to said top members and means arranged in said extension and adapted to move in said slots, whereby to secure said extensions firmly to the top members, substantially as and for the purpose set forth.

4. A clothes hanger comprising an upper member having the form of a conventional hanger, a cross bar formed with recesses therein and being fixedly secured to said hanger, block members slidably mounted upon the cross bar, a vertical rod slidably extending through the said hanger and cross bar, crosswise arranged members pivotally attached to the vertical rod and block members, top members hingedly secured to the hanger, and bars pivotally attached to said top members and to the crosswise members, said bars being arranged upon the side of the cross bar and being adapted to slide in the recesses formed in the latter.
